UNITED STATES PATENT OFFICE.

JAMES E. SCOTT, OF LOUISVILLE, KENTUCKY, ASSIGNOR OF TWO-THIRDS TO
BENSON E. BROWN AND H. KIRK WHITE, JR., OF DETROIT, MICHIGAN.

WINDOW-SASH.

SPECIFICATION forming part of Letters Patent No. 734,436, dated July 21, 1903.

Application filed February 17, 1903. Serial No. 143,822. (No model.)

To all whom it may concern:

Be it known that I, JAMES E. SCOTT, a citizen of the United States, and a resident of Louisville, in the county of Jefferson and State 5 of Kentucky, have made a certain new and useful Invention in Window-Sashes; and I declare the following to be a full, clear, and exact description of the same, such as will enable others skilled in the art to which it applies to make and use the invention, reference being had to the accompanying drawings, and to letters of reference marked thereon, which form a part of this specification.

Figure 1 is a fragmentary side view of the 15 invention as applied. Fig. 2 is a similar view from the front. Fig. 3 is a section on the line 3 3, Fig. 2. Fig. 4 is a similar view of a modified form of the invention apart from the window-casing. Fig. 5 is a fragmentary perspective view of the same.

This invention relates to window-sashes; and it consists in the novel construction and combinations of parts, as hereinafter set forth.

The object of the invention is to provide a 25 sash-slide for car and other windows designed for the prevention of the ingress of air and dust, to avoid rattling, and to afford facilities for raising and lowering the sash and to obviate the difficulties arising from the swelling 30 of the wood when wet, provision being made to secure these objects through the elastic play of a slide device between the sash and sash-groove.

In the accompanying drawings, the letter 35 *a* designates the window-frame; *b*, the sash-groove in the window-frame, made sufficiently wide to accommodate the offset spring-flanges *c*.

d is a spring-metal slide-strip having channel form to receive the edge of the sash and having its lateral expanded or offset portions or side walls reversely bent or curved to provide the cylindrical offsets or shoulders *e* and extending therefrom obliquely, but having a 45 substantially parallel relation thereto, the flanges *c*, there being a lateral interval *g* between each side of the channel portion and the flange. The flanges extend beyond the base of the channel portion, thereby provid-

ing an interval *g'* between said channel portion and the wall of the window-frame groove in order to give an easy elastic movement to the sash, while at the same time closing the sash-groove of the window-frame against air-drafts and dust. Usually the slide-strip is 55 made in one piece; but it may be made in two parts, each having a reversely-bent offset flange, the two parts when applied to a sash having the channel form, as when made in one piece.

Having described this invention, what I claim, and desire to secure by Letters Patent, is—

1. In an antirattling and dust-excluding device for window-sashes, a metallic strip having the sash-receiving channel, the side walls of said channel having reverse spring extensions including an interval and having a curved connection between each of the same and each side wall, substantially as specified. 65

2. In an antirattling and dust-excluding device for window-sashes, a metallic strip having the sash-receiving channel and the offset flanges reversely curved and extended beyond the base of said channel, substantially 75 as specified.

3. A metallic strip of channel form, having reversed offset flanges connected to the channel-piece by cylindrical bends, substantially as specified.

4. A metallic strip of channel form, having offset flanges extending obliquely from cylindrical shoulder-bends, substantially as specified.

5. The combination with a window-frame 85 having the groove, of the window-sash provided with a channelled edge strip, the side walls of said strip having reverse spring extensions having mutual spring-contact with the side walls of the frame-groove, substantially 90 as specified.

In testimony whereof I affix my signature in presence of two witnesses.

JAMES E. SCOTT.
